DIAL CONTROL

Original Filed June 3, 1927

Inventor

Harold R. Hayden

By his Attorney

Sheldon H. Graves

UNITED STATES PATENT OFFICE

HAROLD R. HAYDEN, OF BROOKLYN, NEW YORK, ASSIGNOR OF ONE-HALF TO ABRAHAM E. VAN DOREN

DIAL CONTROL

Original application filed June 3, 1927, Serial No. 196,244. Divided and this application filed September 26, 1928, Serial No. 309,282.

This invention relates to radio receiving apparatus and more particularly to dials or indicating devices, such as are employed for tuning the system to receive desired incoming 5 signals.

The principal object of my invention is to provide a radio receiving apparatus with a dial having the indications thereon formed of luminous material visible in the dark. 10 Heretofore in order to illuminate dials on radio receiving sets it has been customary to employ miniature electric lamps which are connected in circuit to the source of the current which supplies the vacuum tubes of the 15 set. When the lamp is connected in series with the vacuum tubes the system can be operated only when the lamp is illuminated and on failure of the lamp the system ceases to function. When the lamp is connected in 20 shunt to the tube circuits switching on or off of the lamp or failure of the lamp is apt to cause changes in the voltage applied to the tube circuits which interferes with the efficient operation of the system. By the use 25 of a dial provided with luminous characters or connections the disadvantages above noted are overcome.

While I am aware that it has been proposed to apply luminous material to various 30 devices for the purpose of rendering them visible in the dark, I am unaware that luminous material has ever been employed on the dials of radio receiving sets above described.

35 The specific features of my invention relate to the particular markings and arrangement of markings of luminous material on the dial with a view to permitting a ready and accurate reading of the dial setting, to the protection of the luminous material from dirt and wear and also to features of construction as will be more particularly pointed out hereafter.

Also, other objects and advantages of my 45 invention will appear from the following description taken in connection with the accompanying drawing wherein:

Figure 1 is a front elevation of one form of dial embodying my invention,

50 Figure 2 is a vertical transverse sectional

view of the structure shown in Figure 1 and,

Figure 3 is a detail view showing the form and relative arrangement of certain of the parts shown in Figures 1 and 2, one of these 55 parts having marked thereon call letters of broadcasting stations.

The dial shown in the drawing comprises a casing 10, consisting of a face plate 11, and a back plate 12, adapted to be secured 60 to the face plate by screws 13. The back of face plate is recessed so as to provide a space or chamber 14, inside the casing 10. The back and face plates of the casing 10 are provided with central openings 16 and 17, respectively, which form bearings for a rotary collar 18, to which is secured a semi-circular plate 20, located in the space 14. Rotation 65 of the collar 18, serves to rotate the plate 20 and bring the numbered graduations 22, on 70 the peripheral margin of the dial plate into view through an opening 24, formed in the upper part of the face plate 11. The upper wall of the opening 24 is formed with a downwardly tapered projection 23, which serves 75 as a pointer to indicate the position of the dial 20. The graduations 22 are marked on the plate 20 with luminous paint so as to be visible in the dark.

Extending through the collar 18, and 80 adapted to be actuated thereby, is a shaft 25, which is adapted to carry at its inner portion the movable plates of a tuning condenser, not shown. The collar 18 projects forwardly 85 through the opening 17 of the face plate 11 and has secured thereto, at its outer end, an operating knob 26, formed of an inner metal bushing 27 around which is molded a base 28. The knob 26, the collar 18 and shaft 25 are secured together by means of a screw 30, 90 which passes through the knob and collar and engages the shaft 25.

Secured to the bushing 27 is a pointer or arm 31 which is adapted to cooperate with a segmental strip 32, upon which may be 95 marked indicia, such as the call letters 40 indicating different broadcasting stations. Strip 32 is set into the face of the plate 11, as shown in section in Figure 2, and is formed with a suitably roughened outer surface so 100

that it may be easily marked. The surface of the strip 32, along its inner margin, is coated with luminous material forming an arcuate band 36, visible in the dark. The pointer 31, 5 extends over the band 36, and hides from view a small portion of the band. By observing what portion of the band 36, is hidden from view by the pointer 31, it is possible for an operator in the dark to estimate the angular 10 position of the pointer or the adjustment of the condenser. This is of considerable assistance in case the numbers on the dial 20 cannot be accurately read. An operator can easily ascertain the position of the stationary pointer 23, relative to some number on the movable dial 20, and by observing the position of the movable pointer over the band 36, he can judge accurately what the number is.

It is to be noted that luminous material 20 which forms the markings on the dial 20, being enclosed in the casing 10 is protected from dirt and wear.

The face plate 11 is formed with a top projecting portion 38 having an opening 29 therethrough, adapted to receive a screw 40 for securing the casing 10 to the front panel of the cabinet.

This application is a division of my co-pending application, Serial Number 196,244 30 filed June 3, 1927.

Having now described my invention, what I claim and desire to secure by Letters Patent is:

1. A dial control comprising a stationary 35 plate, a rotary member mounted in said plate, a pointer secured to said member and movable over said plate and a band of luminous material on said plate, located behind said pointer.

40 2. A dial control comprising a casing having a chamber therein, a member rotatably mounted in said casing, a dial in said chamber, movable with said member, and having graduations thereon formed of luminous material, said casing being formed to render visible from the outside graduations on said dial, a pointer secured to said member and movable over the outer face of said casing, means forming a surface upon which the dial 45 indications may be marked, said means being adapted to cooperate with said pointer to indicate the position of said member and an arcuate band of luminous material on said casing behind said pointer.

55 3. A dial control comprising a rotary member, a dial and pointer movable with said member, a stationary pointer cooperating with said dial to indicate the position of said member and a stationary dial cooper- 60 ating with said movable pointer to indicate the position of said member.

4. A dial control comprising a rotary member, a dial and pointer movable with said member, a stationary pointer cooperating 65 with said dial to indicate the position of said

member, a stationary dial cooperating with said movable pointer and indicia of different kinds on said respective dials.

5. A dial control comprising a casing having a chamber therein, a member rotatably mounted in said casing, a graduated dial in said chamber secured to and movable with said member, the wall of said casing being formed with an opening to render visible, 70 graduations on said dial, and a pointer secured to said member and movable therewith, outside said casing, the outside of said casing being formed with an arcuate portion adapted to cooperate with said pointer to indicate the position of said member, said portion 75 being formed with a surface which may be easily marked.

6. In a dial control, a face plate, a member rotatable relative to said face plate, a graduated dial behind said face plate, secured to and movable with said member, said face plate being formed with an opening to render 80 visible graduations on said dial, a pointer secured to said member and movable therewith in front of said face plate, said face plate being formed with an arcuate portion adapted to cooperate with the pointer to indicate the position of said member and call letters of different broadcasting stations along said arcuate portion.

95 7. In a dial control, a rotary shaft, a hub adjustably mounted on said shaft, a dial rigid with said hub and covering substantially 180° of arc; an arm rigid with said hub and extending from said shaft in a direction opposite to the radius intersecting said arc at its centre and stationary means cooperating with said dial and arm to permit adjustment of said shaft to the desired angular setting.

100 8. In a dial control a face plate, a rotary shaft extending outwardly through said face plate, a hub on said shaft extending outwardly through said face plate, a dial rigid with said hub, positioned back of said face plate, a pointer rigid with said hub, positioned in front of said face plate, said dial covering substantially 180° of arc and said pointer extending from said shaft in a direction opposite to the radius intersecting said arc at its centre, said face plate being formed 105 with an opening to permit graduations on said dial to be visible through said face plate, and means cooperating with said pointer to permit adjustment of said shaft to the desired angular setting.

110 9. In a dial control a face plate, a rotary shaft extending outwardly through said face plate, a hub on said shaft extending outwardly through said face plate, a dial rigid with said hub, positioned back of said face plate, an arm rigid with said hub, said dial covering substantially 180° of arc and said arm extending from said shaft in a direction opposite to the radius intersecting said arc at its centre, said face plate being formed 115

120

125

130

with an opening to permit graduations on said dial to be visible through said face plate, means cooperating with said arm to permit adjustment of said shaft to the desired angular setting, a knob positioned over the outer ends of said hub and shaft, and a screw extending through said knob and hub for securing said knob and hub to said shaft.

10. A dial control comprising a casing having a chamber therein, a member rotatably mounted in said casing, a dial in said chamber secured to and movable with said member, said dial having position indicating means thereon, the wall of said casing above said 15 rotary member being formed with an opening to render visible the indicating means on said dial, an arm secured to said rotary member and movable therewith, said casing being formed beneath said rotary member with an 20 arcuate portion and a plurality of means along said arcuate portion cooperating with said arm for the positioning of said dial at different settings.

Signed at New York, in the county of
25 Kings and State of New York this 25th day
of September, A. D. 1928.

HAROLD R. HAYDEN.
